UNITED STATES PATENT OFFICE.

FREDRIC M. PARKER, OF WORCESTER, MASSACHUSETTS, ASSIGNOR TO
WILLIAM JAMES HOGG, OF SAME PLACE.

DESIGN FOR CARPET.

SPECIFICATION forming part of Design No. 24,303, dated May 14, 1895.

Application filed April 5, 1895. Serial No. 544,674. Term of patent 3½ years.

To all whom it may concern:

Be it known that I, FREDRIC M. PARKER, a citizen of the United States, residing at Worcester, in the county of Worcester and 5 State of Massachusetts, have invented and produced a new and original Design for Carpets, of which the following is a specification.

My invention relates to a design to be worked into or upon carpeting or similar fabrics, and I do hereby declare that the drawing accompanying this specification gives and conveys to any person skilled in the art of carpet-weaving a sufficiently clear understanding of the same to enable such person to use 15 my invention.

The drawing is a face view of a carpet embodying my new design.

The drawing illustrates a body and a border. The body A is characterized by a number 20 of small oval figures. These figures are located obliquely with respect to each other, and are outlined by curves or branches of conventionalized stem-work.

The border B is characterized near its inner edge with a configuration conforming to

the configuration employed in the body, and near its outer edge by a number of curves enclosing conventionalized flower forms. These curves are shaded off into a uniform ground-work at the outer edge of the border. 30

The colors employed for the different portions of this design may be varied to suit the taste or convenience of the manufacturer.

What I claim, and desire to secure by Letters Patent of the United States, is— 35

1. In a design for carpeting, the body A, substantially as shown.
2. In a design for carpeting, the border B, substantially as shown.
3. The design for carpets, consisting of the 40 body A and the border B, substantially as shown.

In testimony whereof I have hereunto set my hand in the presence of two subscribing witnesses.

FREDRIC M. PARKER.
